UNITED STATES PATENT OFFICE.

SWAN F. ANDERSON, OF ROCKFORD, ILLINOIS, ASSIGNOR OF ONE-THIRD
TO ELMER LUTZHOFF, OF ROCKFORD, ILLINOIS.

BIT FOR CARVING-MACHINES.

SPECIFICATION forming part of Letters Patent No. 788,873, dated May 2, 1905.

Application filed February 20, 1905. Serial No. 246,596.

To all whom it may concern:

Be it known that I, SWAN F. ANDERSON, a citizen of the United States of America, residing at Rockford, in the county of Winnebago 5 and State of Illinois, have invented certain new and useful Improvements in Bits for Carving-Machines, of which the following is a specification.

My invention relates to bits or cutting-tools and holders therefor of carving-machines. Its object is to provide a bit or tool holder and interchangeable tools therefor having tangs especially adapted to be quickly inserted into and secured in or detached from such holder; and it consists, essentially, of a combination of an inwardly-tapering cup-shaped socket furnished with an integral supporting-shank extending from the center of the outside of the bottom thereof and having a screw-hole 15 tapped into the center of the inside of such socket-bottom, a tapering binding-plug the counterpart of but of less transverse diameter than the cup-shaped socket and terminating at its apex in a screw fitted to enter the screw-hole 20 therein and provided with transverse opposite tool-retaining lugs, and cutting-tools 25 furnished with semicylindrical tapering tangs corresponding in shape to the tapering annular recess formed by the socket and binding-plug and having transverse opposite notches 30 in their edges to admit and engage the lugs on the binding-plug.

Referring to the accompanying drawings, which form a part of this specification, Figure 1 is a central vertical partial section of cutting-tools and their holder embodying my invention. Fig. 2 is a section at the dotted line 2 2 in Fig. 1 of parts there shown. Fig. 3 is a section at the dotted line 3 3 in Fig. 2 of 35 parts there shown. Fig. 4 is an isometrical detail view of the cutting-tools and their binding-plug shown in the preceding views.

Like letters of reference indicate corresponding parts throughout the several views. 40 A is an inwardly-tapering cup-shaped socket

furnished with an integral supporting-shank A', extending from the center of the outside of the bottom thereof and having a screw-hole A² tapped into the center of the inside of such socket-bottom. 50

B is a tapering binding-plug the counterpart of but of less transverse diameter than the cup-shaped socket A and terminating at its apex B' in a screw B², fitted to enter the screw-hole A² therein and provided with transverse opposite tool-retaining lugs B³ and a driving-slot B⁴. 55

C D are cutting-tools furnished with semi-cylindrical tapering tangs C' D', corresponding in shape to the tapering annular recess a, 60 formed by the inner wall of the socket A and the binding-plug B, and having transverse opposite notches C² D² in their edges to admit and engage the lugs B³ on such binding-plug B. 65

Having fully described my invention, what I claim as new, and desire to secure by Letters Patent, is—

1. In combination, an inwardly-tapering cup-shaped socket, furnished with an integral supporting-shank extending from the center 70 of the outside of the bottom thereof and having a screw-hole tapped into the center of the inside of such socket-bottom, a tapering binding-plug, the counterpart of but of less transverse diameter than the cup-shaped socket and 75 terminating, at its apex, in a screw fitted to enter the screw-hole therein and provided with transverse opposite tool-retaining lugs and cutting-tools furnished with semicylindrical tapering tangs, corresponding in shape 80 to the tapering annular recess, formed by the socket and binding-plug, and having transverse opposite notches in their edges to admit and engage the lugs on the binding-plug. 85

2. In combination, an inwardly-tapering cup-shaped socket A, furnished with an integral supporting-shank A' and having a screw-hole A² tapped thereinto, a tapering binding-plug B terminating, at its apex B', in a screw B² fitted to enter the screw-hole A² therein 90

and provided with transverse opposite tool-retaining lugs B³ and cutting-tools C D furnished with semicylindrical tapering tangs C' D' and having transverse opposite notches C² D² in their edges to admit the lugs B³ on the binding-plug B, substantially as described.

In testimony whereof I have signed my name

to this specification in the presence of two subscribing witnesses.

SWAN F. ANDERSON.
